UNITED STATES PATENT OFFICE.

DAVYDD C. HUGHES, OF CHICAGO, ILLINOIS.

TOY ENGINE.

1,366,883.

Specification of Letters Patent. Patented Jan. 25, 1921.

Application filed May 1, 1919. Serial No. 293,944.

To all whom it may concern:

Be it known that I, DAVYDD C. HUGHES, a citizen of the United States, residing at Chicago, in the county of Cook and State of Illinois, have invented new and useful Improvements in Toy Engines, of which the following is a full, clear, concise, and exact description, reference being had to the accompanying drawing, forming a part of this specification.

My invention relates to improvements in toys, and especially to toy engines of that type operated by steam.

One of the objects of my present invention is to provide a steam-operated toy engine which can be economically constructed and which shall be of few parts and which shall be safe in operation. One of the objections to the present type of toy engine is the danger from fire. In the present commercial type of toy steam engine, the boiler is heated by means of alcohol, benzin, or like burners, which in the hands of children become fire hazards.

25 In the type of engine invented by me I provide electrical means for heating the boiler, which may be readily attached to any ordinary lamp socket, and the fire danger is thereby entirely eliminated.

30 For the purpose of disclosing my invention, I have illustrated one embodiment of the same in the accompanying drawings, in which—

Figure 1 is an elevation of an engine embodying my invention, parts of the same being shown in section;

Fig. 2 is a sectional view of the same;

Fig. 3 is a detail section taken on the line 3—3 of Fig. 1; and

40 Fig. 4 is a detail section on the line 4—4 of Fig. 2.

In the embodiment illustrated, I provide a base 1, preferably cast and having a portion of its sides 2 cut away to form legs. Within the sides is formed a ledge or shoulder 3, to which may be secured a cover plate 4, preferably interiorly lined with some insulating material and secured in position by suitable screws 5. The base 1 has a central circular opening, into which projects the lower open end of a hollow, cuplike bottom 6 for the boiler. The bottom has an annular shoulder 7 which rests on the base and on the under side of the top 8 is provided with an internally screw-threaded lug 9 into which the lower end of a bolt 10 takes. The lower end

of the bolt passes through a clamp 11 on the under side of the base, which clamp bridges the opening in the base, and a nut 12 on the bolt is provided for drawing and holding the parts together. Arranged within the cuplike bottom is a heat coil comprising a cylindrical insulating base 13, on which are wound the resistance wires 14 of the coil. A suitable insulating cover 15 surrounds the coil, and a split clamping tube 16 arranged within the coil incloses the same. The opposite edges of the tube are provided with lugs 17, alternate lugs being punched out of the plane of the edges and arranged between the edges, and sliding in the groove formed by the displacement of the lugs is a wedge 18 which spreads the tube and thereby holds the same tightly in place. The two ends of the resistance wire are connected on the under side of the base to the binding-posts or other terminals. Each of these terminals comprises a post 19 screw-threaded at its lower end and projecting through suitably enlarged openings in the base. Nuts 20 and 21 clamping the base secure the posts in position, and interposed between the nuts and the base are insulating washers 22 countersunk in the base to not only insulate the nuts from the base but also to hold the post 85 in spaced relation to the sides of the openings through which the posts project. A third nut 23 secures the end of the resistance coil to the post.

The boiler 24, preferably formed of sheet-metal tubing and having a top 25, is secured over the bottom 6 and tightly fits around a spacing flange on the bottom near the lower end thereof. This spacing flange spaces the side wall of the bottom 6 from the sides of the boiler and permits the water in the boiler to completely surround the heat coils. The boiler on one side is provided with the usual water glass 26, which is held in position between the glass holders 27 and 28 extending from and communicating with the boiler. A whistle 29 is mounted on the glass-holder 28 and is controlled by a suitable valve 30. The engine cylinder 31 is vertically disposed and secured in the top of the boiler, and the cylinder and valve casing are preferably made in a single casting. The steam admission port 32 for the cylinder consists merely of a hole bored through the casting into the cylinder and communicating with the opening in the boiler. A reciprocating slide valve 33 for the cylinder operates in a vertically extend-

ing opening in the cylinder casting and is provided with an admission opening 34 extending therethrough and adapted at predetermined intervals to aline with the port 32. 5 This valve is also provided with an exhaust opening 35, which at predetermined intervals alines with the opening 32 and communicates through the hollow end of the valve 33 with the atmosphere.

10 The admission of steam to the cylinder 31 is controlled by a hand valve 36, which screws into a cross opening in the cylinder casting and has a stem by which the opening and closing of the opening 32 may be controlled.

15 The piston 37 of the cylinder is connected by connecting rod 38 with the fly-wheel 39 mounted on a shaft 40. This shaft extends through the boiler, a tube 41 forming the bearing therefor and fitting tightly in the openings in the sides of the boiler. An eccentric 42 is also mounted on the shaft, the ring 43 of which is connected by a rod 44 with the valve 33 for operating the same, 20 and on the end of the shaft opposite the fly-wheel is mounted a suitable driving pulley 45.

25 Water is admitted to the boiler through an opening in a bung 46 secured in the top. This bung is interiorly screw-threaded to receive a closing plug 47 provided with a blow-off opening 48 having a restricted neck forming a seat for a ball valve 49, which valve is held in position by a coiled spring 50, which, 30 in turn, is held in position by in-turned prongs 51 integrally formed on the top of the plug 47.

35 Having thus described my invention, what I claim as new and desire to secure by Letters Patent, is:

40 1. In a toy engine, the combination with a base having a centrally disposed opening therein, of a cylindrical bottom member having an annular flange resting on said base 45 and a portion thereof projecting through said opening, an annular resistance coil arranged within said bottom member and lying in close proximity to the side walls thereof, a central post secured to said bottom member, a clamp bridging the opening in said base and secured to said central post for

50 holding said bottom member in position, a boiler fitting over said bottom member and having its side walls spaced apart from the walls of said bottom member to allow the 55 water to completely surround said bottom member, and a cylinder having a piston operating therein and receiving steam from said boiler.

55 2. In a toy engine, the combination with a 60 base, of a cylindrical bottom member, an annular heat coil disposed within said bottom member and lying against the walls thereof, the lower end of said bottom member projecting into an opening in said base, 65 a central post connected to said bottom member, a bridge on the under side of said base spanning the opening in the base and connected to said central post, and a boiler body fitting over said bottom member and spaced 70 apart from the side walls thereof.

65 3. In a toy engine the combination with a supporting frame of a detachable watertight casing of inverted cup shape containing a heater element, and a cylindrical upright boiler shell mounted on said casing, the latter being provided with an outstanding flange adjacent to its lower edge and fitting fluid-tight within the lower end of said shell, whereby the lower part of said shell 80 is spaced from the main wall of said casing and a large area of heater casing surface is presented to the surrounding water.

75 4. In a toy engine the combination with a supporting frame of a water-tight rim- 85 flanged heater casing of inverted cup shape containing a heater element, and a cylindrical upright boiler casing surrounding the main body of and tightly embracing the flange of said heater casing, whereby the 90 main wall of the heater casing is spaced from said boiler casing, said frame being open for ready access underneath and provided with a cross-bar, and a screw extending upward through said cross-bar and engaging the middle part of the end wall of 95 said heater casing for securing same to said frame.

80 In witness whereof, I have hereunto subscribed my name.

DAVYDD C. HUGHES.
